GUIDEWAY FOR RECIPROCATING ENGINES, PUMPS, OR THE LIKE

Original application filed April 24, 1924, Serial No. 708,615. Divided and this application filed March 10, 1926. Serial No. 93,568.

My invention relates to guideways for reciprocating engines, pumps or the like.

One of the objects of the invention is to provide a simple, practical and advantageous construction of guideways for reciprocating pumps or engines and like devices.

Other objects of the invention is to support the weight of the reciprocating or moving parts, such as the piston rod or cross head 10 or connection in an effective and adequate manner; to avoid undue strains, wear and friction; and to permit ready lubrication and adjustment.

In the accompanying drawings Fig. 1 is a 15 side elevation of a pump having a guideway embodying my invention;

Fig. 2 is an end elevation of the same;

Figs. 3, 4 and 5 are views of details of construction, Fig. 3 being taken on line 3—3 in 20 Fig. 1, and Fig. 4 being taken on line 4—4 in Fig. 5.

Referring to the drawings, I show a reciprocating pump particularly adapted for use as a stuff pump for pumping paper making 25 material, often called stuff, although it will be understood that the invention may be applied to other forms of apparatus. This pump has a base member 1 supporting a plurality, as for example, three, cylinders 2, 2a and 2b, which are horizontally disposed and arranged side by side. These cylinders 2, 2a and 2b are provided with reciprocating pistons, 3, 3a and 3b, connected with connecting rods 4—4, which connection rods 4—4 are driven by cranks spaced 120 degrees apart 30 on a rotary shaft 5.

Below the cylinders 2, 2a and 2b are casings 7, 7a and 7b, respectively, and these casings form chambers for the stuff and are connected with stuff inlets 8—8 by a duct or passage formed by the end portion 9 of the base 1. The casings 7, 7a and 7b are conveniently cast integral with the respective cylinders 2, 2a and 2b, and are open at their upper ends 45 so as to communicate with said cylinders 2, 2a and 2b, permitting the stuff to enter either or both of the inlets 8—8, and flow into the stuff chambers formed by casings 7, 7a and 7b, and thence into the cylinders. The 50 flow of the stuff, however, is controlled by

ball valves 10—10, seated on valve seats 11—11 at the base of the several stuff chambers 7, 7a and 7b, said ball valves being guided in their vertical movement by guide ribs or vanes 12—12. For permitting access 55 to the interior of stuff chambers 7, 7a and 7b, the same are provided with removable doors 14—14 held in place by handles 15—15 on threaded rods 16—16.

Above the cylinders 2, 2a and 2b are casings 17, 17a and 17b, forming stuff outlet chambers, and these are united by pipes 18 and 18a into a single discharge pipe 19, through which the stuff material is discharged. These stuff outlet chambers 17, 17a and 17b are preferably cast together and are in communication with the respective cylinders, and are provided with ball valves 20—20 controlled by guide vanes or ribs 21—21, and arranged to control the outflow or 60 escape of stuff from the several cylinders with which they are respectively in communication. These stuff outlet chambers are also 65 preferably provided with side doors 22—22 held in position by handles 23—23 on threaded rods 24—24, allowing access to the interior of said chambers for various purposes. The pistons 3, 3a, and 3b work in stuffing boxes 25—25 having packing rings 26—26 controlled by adjustable members 27—27, as 70 best shown in Fig. 5. Said piston rods are further supported and guided by guides 29—29 traveling in guideways 30—30. The 75 guides 29 are preferably secured to the pistons 3—3 by annular members 31 having webs 80 32 secured by bolts 33 to flanges 34 formed on the ends of the tubular pistons 3. The webs 32 also serve as a medium of connection between the pistons 3—3 and their guides and the piston rods 4—4, said pistons 4 being 85 preferably secured by ball or universal joints to said webs 32—32, the latter preferably being laterally recessed so as to form chambers for oil 36 for lubricating said ball or universal joints.

The guideways 30 are conveniently formed by upper guide members 30a and lower guide strips 30b bolted to the upper members 30a by bolts 30c, the guides 29 having their outer edges interposed and working between mem- 90 95 100

bers 30a and 30b. The members 30b preferably have their inner ends recessed to form chambers for oil 30d.

Thus it will be seen that in operation the reciprocating pistons 3-3 will have their outer ends advantageously supported, guided and lubricated and also that an effective supporting and guiding connection is made.

This application is a division of my application Serial No. 708,615, filed April 24, 1924, Stuff pumps.

It will be understood that changes and modifications may be made without departing from the spirit of the invention.

15 What I claim is:

1. The combination with the cylinder and piston therefor, of a guide connected with the outer end of the piston and a guideway for said guide, said guide having an annular member surrounding the end of the piston and connected with the same at intervals.

2. The combination with the cylinder and piston therefor, of a guide connected with the outer end of the piston and a guideway for said guide, said guide having an annular member surrounding the piston and also having a web bolted to a flange on the outer end of the piston.

3. The combination with a horizontally disposed cylinder of a piston working therein and a guide supporting and guiding said piston and arranged above the open end of the cylinder, and means for covering said guides and making the same practically waterproof.

35 4. The combination with the piston and cylinder of a cross head member carried at the outer end of the piston and comprising a web-like member extending across the piston and secured to the same, said member having a forwardly extending portion, the upper end of which is extended laterally to form guide members, an elevated guideway in which said guide members travel, and a piston rod connection carried by said cross head member.

5. The combination with a cylinder and an elongated piston, of a cross member forming the outer end of said piston and detachably secured thereto and having an upwardly and 50 forwardly extending supporting portion, said supporting portions having side guide extensions, a guideway for said guides and a universal connection for said piston and a connecting rod.

55 6. The combination with a cylinder and an elongated hollow piston, of a removable end member for said piston having an upwardly and forwardly extending suspension portion, said suspension portion comprising outwardly projecting slideable guides, underhung guideways for said guides, and articulate means for connecting to a connecting rod.

65 7. In combination an elongated hollow piston, a cylinder, a guide for said piston, said guide comprising a cross member forming the

end of said piston and having a central suspensory portion, said portion having at its upper extremity diverging portions provided with slideable guide surfaces, a recessed guideway for said guides and articulate means for connecting a connecting rod.

8. In a device of the class described, the combination with a cylinder open at one end, of a hollow cylindrical piston adapted to reciprocate in said open end, a swinging piston rod, a closure for the outer end of the piston in which the piston rod is pivoted, a guiding and supporting member for the piston forming a part of said end closure, and ways in which said guiding and supporting member reciprocates.

9. In a device of the class described, the combination with a cylinder open at one end, of a hollow cylindrical piston adapted to reciprocate in said open end, a swinging piston rod, a closure for the outer end of the piston in which the piston rod is pivoted, a guiding and supporting member for the piston forming a part of said end closure, and ways in which said guiding and supporting member reciprocates said closure being provided with a recess for oil by which the piston rod joint is lubricated.

10. In a device of the class described, the combination with a horizontal guide member consisting of an upper and a lower portion connected to form a guide channel, of a cross head member having a bearing portion shaped to slide in said guide channel, the said lower portion being so shaped as to form a longitudinal trough for oil at the open side of the guide channel extending throughout the path of said bearing portion and adapted to hold oil at a level above the contacting surfaces of the guide channel and bearing portion.

11. In a device of the class described, the combination with a horizontally extending guide member consisting of an upper and lower portion connected to form a pair of opposed guide channels open on their adjacent sides, of a cross head member having a pair of bearing portions shaped to slide in said guide channels, said lower portion shaped so as to have a flange for each guide channel extending upwardly above but spaced away from said guide channel so as to form a pair of longitudinal troughs for oil at the open sides of the guide channels extending throughout the path of said bearing portions and adapted to hold oil at a level above the contacting surfaces of the guide channels and bearing portions.

12. In a device of the class described, the combination with a horizontally extending guide member consisting of an upper and lower portion connected to form a pair of opposed guide channels open on their adjacent sides, of a cross head member having a pair of bearing portions shaped to slide in said

guide channels and having a central web extending upward between said guide channels, thence laterally on each side, and thence downwardly to the pair of bearing surfaces, 5 said lower portion shaped so as to have a flange for each guide channel extending upwardly above but spaced away from said guide channel so as to form a pair of longitudinal troughs for oil at the open sides of 10 the guide channels extending throughout the path of said bearing portions and adapted to hold oil at a level above the contacting surfaces of the guide channels and bearing portions.

15 13. In a device of the class described, the combination with a horizontally extending guide member consisting of an upper and lower portion connected to form a pair of opposed guide channels open on their adjacent sides, of a cross head member having a pair of bearing portions shaped to slide in said guide channels and having a central web extending upward between said guide channels, thence laterally on each side, and thence 20 downwardly to the pair of bearing surfaces, 25 said lower portion shaped so as to have a flange for each guide channel extending upwardly above but spaced away from said guide channel so as to form a pair of longitudinal troughs for oil at the open sides of 30 the guide channels extending throughout the path of said bearing portions and adapted to hold oil at a level above the contacting surfaces of the guide channels and bearing portions, 35 said upper portion extending entirely across the cross head member to protect the same and having a concave underside to accommodate the horizontally extending portions of the web.

40 In witness whereof, I hereunto subscribe my name this 15th day of February, A. D., 1926.

ALONZO ALDRICH.
